UNITED STATES PATENT OFFICE.

CHARLES H. BELLARS, OF LYNDHURST, NEW JERSEY.

MEANS FOR CONSTRUCTING CONCRETE WALLS.

No. 821,277.

Specification of Letters Patent.

Patented May 22, 1906.

Application filed January 23, 1906. Serial No. 297,401.

To all whom it may concern:

Be it known that I, CHARLES H. BELLARS, a citizen of the United States, residing in Lyndhurst, in the county of Bergen and State 5 of New Jersey, have invented a certain new and useful Improvement in Means for Constructing Concrete Walls, of which the following is a specification.

The invention relates to the molds employed in forming the walls; and the object of the invention is to provide sectional molds adapted to match together and be shifted upward as the walls are built; means for supporting and holding the molds in position on the walls and for forming the required openings, as for windows and doors, and also for ornamenting the faces of the walls, if desired, all of which means shall be easily handled and simple and economical in operation.

20 The invention consists in certain novel features and details of arrangement and construction by which the above objects are attained, to be hereinafter described.

25 The accompanying drawings form a part of this specification and show a preferred form of and method of using the apparatus.

Figure 1 is an elevation showing a corner of a building in process of construction with the improved molds. Fig. 2 is a vertical section on a larger scale through a portion of a wall, showing the moldboards and holding means in elevation. Fig. 3 is an elevation showing a portion of the inner face of one of the moldboards for the exterior face of the 35 wall. Fig. 4 is a vertical cross-section through the same board and a portion of an adjacent board. Fig. 5 is an elevation showing an attachment for the same board. Fig. 6 is a transverse section taken on the line 6 6 40 in Fig. 5, and Fig. 7 is a corresponding side view. Fig. 8 is a modified form of the attachment. Fig. 9 is a cross-section on the line 9 9 in Fig. 8, and Fig. 10 is a corresponding elevation. Fig. 11 is a front view, partly 45 in vertical section, showing the molds for a window-opening. Fig. 12 is a horizontal section on the line 12 12 in the preceding figure, and Fig. 13 is a corresponding vertical section. Fig. 14 is a vertical section through 50 a portion of the wall and interior and exterior moldboards corresponding to Fig. 2, but on a much larger scale. Fig. 15 is a side view showing the holding means, and Fig. 16 is a horizontal section showing the same parts 55 in plan view. Fig. 17 is a horizontal section through a corner of the wall, showing the

junction of the interior moldboards and the exterior moldboards. Fig. 18 is a horizontal section through the exterior moldboards at their junction. 60

Similar letters of reference indicate like parts in all the figures.

The wall M is of "concrete," by which is meant the composition of cement, sand, and other materials usually employed in structures of this character and which may be colored, if desired, to imitate various kinds of stone. The exterior moldboards shaping the outer face of the wall are marked A and the interior moldboards for the inner or unexposed face of the wall are marked B. Each is in the form of a long strip, preferably of wood, faced with sheet metal. They are held apart by bolts C a distance equal to the thickness of the wall to be built and the 70 space between filled with the concrete properly conditioned and tamped. Exterior and interior moldboards are added by placing them on the upper edges of the first and the space thus provided similarly filled until a 75 number, five are shown, are in place and filled and the concrete is set or hardened sufficiently to support itself reliably with the bolts embedded therein.

The uppermost board of each series is allowed to remain in place, held by its bolts thus embedded, while the others are removed by withdrawing the lower bolts and again superposed to form a new space which is similarly filled with concrete, and so on, until 80 the wall has risen to the desired height, the wall thus serving to support the two series of moldboards during the construction and avoiding the labor and expense of building scaffolding or complete molds for the wall, as 85 is the usual practice.

It is apparent that means must be provided for insuring uniform wall thickness and perpendicularity and also for supporting each series of moldboards. This is accomplished 90 by stays D, preferably of heavy sheet metal bent to channel form and each having open slots or inclined notches c in its edges, in which are received the bolts C, which may be simple bolts threaded at the ends to receive 95 nuts, (indicated by the dotted lines at C' in Fig. 14,) but preferably are tubes threaded at each end and engaged by spur gear-wheels D², mounted on studs D' in the trough-like openings in the stays D and turned by a suitable wrench applied on squares D² on the gear-wheels, thus permitting the stays to be 100 105 110

drawn together, as desired, and clamp the moldboards securely to the wall. The gear-wheels are then locked frictionally by nuts D¹ on the studs D'. The stays are thus equipped 5 at both ends and permit the upper ends to be adjusted, as necessary, to insure plumb wall-faces. Each bolt C is preferably equipped with dogs C², pivoted within the tubular bolt and arranged to be swung outwardly through 10 slots c' by a rod C³, forced axially through the bolt. Thus arranged the dogs C² on the lower bolt are engaged in the concrete and hold the lower ends of the stays reliably. When this 15 portion or "course" of the wall is completed and the upper bolt embedded, the stays are released and shifted upward, the lower bolt being removed by withdrawing the rod and permitting the dogs to swing within the tubular bolt as the latter is drawn from the 20 wall by the application of sufficient force. The hole thus left is filled with concrete and the withdrawn bolt replaced through the stays at a higher level and the moldboards again successively superposed within the 25 stays and held thereby in the perpendicular position determined by adjusting the stays and bolt, as above described.

Each moldboard may have holes at proper intervals to receive the bolts, so that the 30 boards of each series may be interchangeable; but I prefer to thus perforate only the boards to be used as the upper and lower boards of each series. The interior moldboards B may be plain strips of suitable lumber; but to insure 35 against warping and wear and also to produce a smooth wall-face they are preferably covered on the upper and lower edges and working face with sheet metal B', zinc, or other non-corrosive material preferred. The 40 edges and working faces of the exterior moldboards A are similarly protected by metal A', which may be embossed, if desired, to produce an ornamented wall-surface. I have shown the exterior moldboards as each having 45 a ridge A² along the upper margin of the working face formed by bending the metal A', producing a correspondingly-shaped longitudinal groove in the wall and provided with vertical ridges A³, making intersecting vertical 50 grooves in the wall, the whole producing an imitation of masonry with channeled joints. The vertical ridges are also of sheet metal with beveled ends matching to the angles of the horizontal ridges A² A² on adjacent 55 moldboards and are secured to the latter at proper intervals by the engagement of the integrally-formed tongues A⁴ A⁴ in slots a a in the horizontal ridges or by projecting tongues of wire A⁵ A⁵ in holes a' a', as may be found 60 preferable.

The window-opening is produced by setting the window-frame E in place and shaping the outer portions of the opening by jamb-pieces F, forming the sides thereof, and the 65 angles at the sill and lintel. The remaining

parts of the sill are shaped by rectangular boxes or tubes F', telescoping into a central box F² and secured by bolts F³ in slots f. The lintel (not shown) is similarly shaped, and the window-cap formed integral with the wall 70 may be ornamented or plain by employing a suitable mold therefor.

The sill projects outwardly from the wall and is produced in a hollow frame G, surrounding a rectangular opening in one of the exterior moldboards A. The frame G, with the moldboard and jamb-pieces F, is held in place and to the interior moldboard B by a clamp H, having a screw H'. Concrete is filled into the frame G from the exterior until 75 more than sufficient to form the projecting portion of the sill is supplied and partially set or hardened. The excess is then cut off by the metal plate or slide G' in the slot g, provided in the upper part of the frame G, producing a smooth exterior face on the sill. The abutting ends of the interior moldboards B, forming the inner angle at the corner, are provided with loosely-fitting metal caps B², arranged to be extended or contracted as may 80 be required to produce the angle, (see Fig. 17,) and the exterior angle is formed by allowing one series of moldboards A to project beyond 85 the intersecting face, while the other series abuts against the first, being held in the desired relation thereto by stud-bolts L, inserted through the notches in one of the stays D and screwed into the ends of the abutting moldboards. The ends of the abutting moldboards are protected by sliding caps A⁶ similar 90 to the caps B² and are firmly held by short screws L', extending through metal braces D⁵ into the uppermost and lowermost of the 95 abutting series.

Swinging hooks J are secured to the outer 100 faces of the stays D for engaging the bolts C while shifting the stays and moldboards, and similar hooks J' on the rear faces of the stays near the ends are received in eyes J² on the moldboards, thus removably securing the 105 moldboards to the stays and causing them to follow the movements of the stays as the latter are adjusted for perpendicularity.

By the use of my invention the expensive 110 construction of the usual complete mold for the wall is avoided, a comparatively small number of the sectional moldboards being sufficient to build a wall of any dimensions, with window and door openings located as desired. All parts of the apparatus are light 115 and easily handled and offer an extremely economical method of wall construction.

Modifications may be made in the forms and proportions of the parts without departing from the principle of the invention or sacrificing its advantages, and parts of the invention 120 may be used without the whole.

A greater or less number of moldboards of greater or less width than shown may be employed in each series, and they may be held 130

in place by other forms of stays secured to the completed portion of the wall by any suitable forms of removable bolts. The metal covering for the boards may be dispensed with. The walls may be chambered or hollowed or reinforced with metallic rods or strips without interfering with the use of the invention, and the exterior of the wall may be plain or variously ornamented. The interior surface may be roughened by correspondingly shaping the surface of the interior moldboards to produce a wall-surface adapted to receive plaster applied directly thereto. One face of the wall may be formed by my moldboards, the other being formed by any approved mold. As before stated, the bolts C may be engaged with the stays by nuts C' C' on the outer and inner faces, by which the stays may be adjusted and held in the desired perpendicular positions, as will be understood.

I claim—

1. In an apparatus for constructing concrete walls, a series of moldboards for the exterior face of a wall, a series of moldboards for the interior face of said wall, stays for each of said series, located opposite each other in pairs, bolts extending through the lower portions of each pair of stays, through the lowermost board of each series and said wall, bolts extending through the upper portions of each pair of stays, and through the uppermost board of each series, and means carried by said bolts for engaging said wall when embedded therein, and means for disengaging said bolts.

2. In an apparatus for constructing concrete walls, a moldboard, a bolt engaging said board and extending therethrough, and means carried by said bolt for engaging a wall when embedded therein, and means for disengaging said bolt.

3. A bolt for the purposes described, consisting of a tube, dogs pivotally mounted therein and constructed to swing through slots in said tube and protrude on the exterior thereof, and a rod adapted to be thrust through said tube and cause such protrusion and to be withdrawn to permit the retraction of said dogs.

4. In an apparatus of the character set forth, a stay, a bolt extending therethrough and having a screw-threaded or annularly-toothed end, a gear-wheel mounted on said

stay and engaged with said screw-threads or 55 teeth, means for turning said gear-wheel and moving said bolt and stay relatively to each other, and a controlling means for holding said gear-wheel against turning.

5. In an apparatus of the character set 60 forth, two series of moldboards, a stay for each series, tubular bolts extending through said stays and the lowermost and uppermost boards of both series, teeth on the ends of said bolts, gear-wheels mounted on studs in 65 said stays and engaged with said teeth, and nuts on said studs for frictionally holding said wheels when desired.

6. In an apparatus of the character described, moldboards constructed to match 70 edge to edge to constitute a series, longitudinal ridges formed on the working faces of said boards, and removable transverse ridges constructed to engage the longitudinal ridges of two adjacent moldboards, substantially as 75 and for the purposes set forth.

7. In an apparatus of the character described, moldboards constructed to match edge to edge to form a series, a metal covering for the working face of each of said boards, 80 longitudinal ridges on said faces formed by shaping said metal covering, removable transverse ridges of sheet metal having tongues engaged in openings in the longitudinal ridges of two adjacent moldboards, substantially as 85 and for the purposes set forth.

8. In an apparatus of the character set forth, an adjustable frame for forming openings in a wall, comprising vertical jamb-pieces, and laterally-extending adjustable 90 hollow telescoping sections connecting said jamb-pieces.

9. In an apparatus of the character described, a moldboard having an opening extending longitudinally thereof, an outwardly-extending frame surrounding said opening, and having a slot in the upper face, and a slide received in said slot, all constructed to serve in forming a window-sill or like projection on a concrete wall, substantially as herein set forth.

In testimony that I claim the invention above set forth I affix my signature in presence of two witnesses.
